UNITED STATES PATENT OFFICE.

HARRY THAYER KINGSBURY, OF KEENE, NEW HAMPSHIRE.

DESIGN FOR A SIDE PLATE FOR TOY CARS.

SPECIFICATION forming part of Design No. 31,100, dated June 27, 1899.

Application filed May 31, 1899. Serial No. 718,914. Term of patent 14 years.

To all whom it may concern:

Be it known that I, HARRY THAYER KINGSBURY, a citizen of the United States, residing at Keene, in the county of Cheshire, State of New Hampshire, have invented a certain new and original Design for a Side Plate for Toy Cars, of which the following is a description, reference being had to the accompanying drawing and to the letters of reference marked thereon.

My invention relates to a new and original design for side plates for toy cars; and it consists of a side plate of the shape and configuration described and illustrated in the accompanying drawing, in which the figure represents a plan view of a side plate for coal-cars embodying my invention.

In the drawing, A represents a flat plate substantially rectangular in shape and having a plain upper edge, but upon its lower edge having a series of projecting ears *b*, while adjacent either end are slots *c*.

Having thus described my invention, what I claim, and desire to secure by Letters Patent, is—

The design for a side plate for toy cars; substantially as shown and described.

In testimony whereof I affix my signature in presence of two witnesses.

HARRY THAYER KINGSBURY.

Witnesses:

W. L. MASON,
C. L. STURTEVANT.
